UNITED STATES PATENT OFFICE

JESSE C. COOK, OF JEFFERSONVILLE, INDIANA, ASSIGNOR TO AMERICAN CREOSOTING COMPANY, OF LOUISVILLE, KENTUCKY, A CORPORATION OF DELAWARE

ADZING MACHINE

Application filed December 16, 1931. Serial No. 581,452.

This invention relates to adzing machines and particularly machines of the type employed in gaining railway ties to provide seats for the reception of the rail plates. More particularly the invention relates to an adzing machine having an arrangement for adjusting the depth of the cut actuatable during the operation of the machine.

The present invention comprises an improvement upon the type of adzing machines already known wherein a mechanism is provided for automatically determining, in accordance with the irregularities in the shapes of the ties, the depths of the cuts to be made, whereby all of the cuts are of substantially uniform depth irrespective of the irregularities in the shape of each tie. In prior art devices of this type, no satisfactory mechanism actuatable during the operation of the machine and independently of the automatically operating mechanism, has been devised for adjusting the depth of the cuts.

Where ties of varying degrees of roughness are to be gained, it is desirable that the machine be adjusted to make a cut in accordance with the nature of the tie whereby, if a tie having a relatively smooth surface is to be gained, a cut of minimum depth may be made, whereas when a tie having a rough surface is to be gained, a cut may be made of such depth that a smooth surface will be produced. According to the present invention, a mechanism is provided which is operable during the working of the machine to adjust the depth of the cut independently of the operation of the automatic means.

An object of the present invention is to provide an adzing machine of the above stated type in which the depth of the cut may be adjusted during the operation of the machine.

Another object of the invention is to provide in an adzing machine of the type where in the depth of the cut is regulated automatically in accordance with the irregularities in the shapes of the ties, a mechanism for manually adjusting the machine to make a cut of predetermined depth. Other objects will appear from the following descrip-

tion taken with the appended drawings, wherein:

Fig. 1 is a view showing a transverse cross-section taken just forwardly of the supporting and cutting mechanisms, the direction of viewing being from front to rear, 55

Figs. 2-9 are detailed views of several modified forms of the adjusting mechanism, and

Fig. 10 is a view showing a mechanism for lifting the ties independently of the cradles. 60

Inasmuch as the machine is substantially symmetrical about a centrally passed plane, and the two halves are therefore enantio-morphic, the following description will be limited to one half of the machine except as to those elements which are not similar in both halves. 65

Referring to the right-hand half of Fig. 1, a base 1 supports a frame 2 on which is rotatably mounted an adzing cutter 3 which is driven by a pulley 4 connected to a suitable source of power (not shown). Encompassing the upper portion of the cutter 3 is a cradle 5 comprising a pair of side rails 6 and a pair of Y-shaped end members 7, 75 each of the latter being carried on a vertically reciprocable pivot pin 8, whereby the cradle is tiltable and vertically reciprocable. 70

The depending portion 9 of each end member is slotted for hinging cooperation with the reduced end 10 of a thrust member 11 which is carried on a vertically reciprocable pivot pin 12. The lower end of the thrust member 11 is provided with a head 13 having a toothed arcuate lower edge 14, the curvature being such that the distance is greater from the pivot pin 12 to the teeth at the center than it is to the teeth at the end portions. 80

Disposed somewhat below the head 13 is a wedge-like member 15 having a horizontal toothed upper edge 16 and an inclined lower edge 17. The wedge member 15 may be formed integrally with a connecting member 18 which is guided on the frame 1 for both horizontal and vertical movement. 85

Pivoted to the lower portion of the frame 2 is a crank 19 having at the end of one arm a bearing member 20 formed with a knife edge adapted to bear against the inclined 100

edge 17 of the wedge member 15 to lift the same into engagement with the head 13 when the crank 19 is rotated in a counter-clockwise direction. The bearing member 20 is threaded in the crank 19 and is provided with a nut 21 whereby its position may be adjusted vertically.

The other end of the crank 19 terminates adjacent an endless chain 22 guided in a track 23 formed in the frame 2 and driven by suitable means (not shown). Carried on the chain 22, at predetermined intervals, are a plurality of cam blocks 24 adapted to bear against a cam rail 25 secured to the adjacent end of the crank 19 to urge the upper end of the crank 19 in a counter-clockwise direction.

The endless chain 22 also carries a plurality of properly spaced abutments 26 which serve to transport the ties to be gained past the cutter 3, rail 27 being disposed above the upper lap of the chain 22 to provide a riding surface for the ties. Disposed above each cradle 5 is a resiliently mounted roller 28 which serves to maintain the corresponding end of a tie 29 in contact with the cradle 5.

A thrust member and crank similar to those seen in Fig. 1 are provided at the rear of the frame member 2 and cooperate with a second Y-shaped member and the near end of the cam rail respectively, in a similar manner.

Referring to the left-hand half of Fig. 1, a wedge member 30 is disposed similarly to the first wedge member 15 but has its lower edge inclined in the same direction. The two forward wedge members 15 and 30 are connected by the connecting member 18 and two similar wedge members (not shown) which cooperate with the rear pushers and cranks (not shown) are connected by a second connecting member 31 which is also guided in the frame 2 for horizontal and vertical movement. The connecting members 18 and 31 are connected by a linkage mechanism 32 to an operating lever 33 by means of which the connecting members 18 and 31 may be reciprocated in a horizontal direction to move the wedges 15 and 30 into and out of the space between the heads 13 and the bearing members 20. The lever 33 and consequently the wedge members 15 and 30 are maintained in any one of several positions by a holding mechanism 34 of known type.

The operation of the machine is as follows (considering only the right-hand portion of the machine):

A tie is fed onto the rails 27 and is pushed therealong by the abutments 26 until it reaches the cradle 5 onto which it rides, being held firmly thereon by the rollers 28 bearing against its top surface.

If the tie is not irregular in shape the cradle 5 remains level and the tie is carried into engagement with the cutter 3. Just

prior to the engagement between the cutter and the tie, the cam block 24 rides onto the cam rail 25 and presses the same outwardly to rock the crank 19 in a counter-clockwise direction. The bearing member 20 lifts the wedge 15 into engagement with the head 13 and the cradle 5 is thereby lifted to raise the tie a predetermined distance. Since the pusher member 11 is in a vertical position, the distance between the pivot 12 and the portion of the head in contact with the wedge is a maximum and the cradle is therefore raised a maximum distance and hence, a cut of minimum depth is made.

If the tie is irregular in shape, the cradle 5 is tilted and, through the agency of the depending portion of the Y-shaped member 7 and the pusher member 11, a corresponding lateral displacement is imparted to the head 13. In such a case, when the crank 19 is rotated to raise the cradle 5, the distance the cradle is raised is less than the maximum distance because of the fact that the distance from that portion of the head 13 engaged by the wedge member 15 is less than the maximum. Thus, it will be seen that a deep cut is made in the tie and further it will be seen that, since the curvature of the toothed head 13 varies from maximum to minimum, the extent the cradle is lifted is dependent upon the degree of tilting of the cradle which, of course, is determined by the extent of irregularity in the shape of the tie.

Where the tie is relatively smooth and it is thus desirable to take only a shallow cut, the handle 33 is operated to move the wedge members 15, 30 to the left as viewed in Fig. 1. The effective thickness of the wedges is thus increased and consequently the cradles are raised a greater distance than when the wedges are in the positions shown in Fig. 1. Where the tie is relatively rough and it is desirable to take a deep cut, the wedges are moved into the positions shown in Fig. 1.

This arrangement for adjusting the extent of elevation of the cradles is operable during the operation of the machine, since only a simple movement of the lever is required to make the adjustment. The adjustment may be made between the engagement of the cutter with two successive ties. It will now be apparent that an operator may be stationed at the machine and, upon observing the motive of each tie, may adjust the lifting arrangement for the most suitable lift whereby a cut of optimum depth for that particular type of tie may be made.

It will be seen from the foregoing that the operation of the adjusting mechanism in no way interferes with the automatic adjustment of the lifting arrangement in accordance with the irregularities in the ties. The manual adjustment may be made whether the automatic adjustment provides for a deep or shallow cut.

If it is desired that no cut shall be made in a tie, the lifting mechanism is adjusted to lift the cradles sufficiently to raise the tie entirely out of contact with the cutters.

In Fig. 2 is shown a modified form of wedge member 15^a wherein there is provided, instead of the inclined lower edge 17, shown in Fig. 1, a stepped lower edge 17^a which cooperates with the bearing member 20^a. This form operates in substantially the same manner as the first form, the wedge member 15^a being moved with respect to the bearing member 20^a to vary the height of the toothed upper edge 16^a with respect to the bearing member 20^a.

Fig. 3 illustrates another form wherein the wedge member 15 is provided with a horizontal lower edge 17^b resting on the crank 19^b and an inclined upper edge 16^b cooperating with the bearing member 20^b to raise or lower the same with respect to the crank 19^b as the wedge member 15^b is moved horizontally. Instead of the wedge member 15^b, shown in Fig. 3, a member 15^c having a horizontal lower edge 17^c and a stepped upper edge 16^c may be provided, as shown in Fig. 4.

A somewhat different arrangement is shown in Fig. 5, wherein there is no adjusting member cooperating with the bearing member 20^d but a wedge member 35 actuated by a crank 36 pivoted to the end of the main crank 19^d determines the position of the cam rail 25^d which in this form, is movable on the crank 19^d. When the adjusting crank 36 is rotated in a counter-clockwise direction, it moves the wedge member 35 upwardly to force the cam rail 25^d away from the main crank 19 and thus, when the cam block (not shown) bears against the rail 25^d the main crank 19^d is rotated through a greater angle than when the wedge 35 is in the position shown.

In Fig. 6, the pivot pin 37 which carries the crank 19^e is mounted in a horizontally displaceable bearing 38 mounted in an eccentric 39, which eccentric 39 is provided with a lever 40 for rotating the same. If the lever 40 is rotated in a clockwise direction, the bearing 38 is moved to the right (as viewed in Fig. 6) and the upper end of the crank 19^e which operates with the cam block (not shown) is displaced to the right. This displacement of the crank 19^e causes the arm which carries the bearing member 20^e to be displaced a greater distance by the passage of the cam block than when the crank 19^e is positioned as shown in Fig. 6.

Fig. 7 illustrates still another form of adjusting means. In this form a head 40 is pivoted to the end of the arm of the crank 19^f and carries a plurality of radially arranged bearing members 20^f of graduated lengths. The adjustment is made by rotating the head 40 to bring that one of the bearing members 20^f having the desired length

into engagement with the head (not shown) of the pusher member (not shown).

As shown in Fig. 8, a cam-like head 41 may be provided instead of the head 40 carrying the several bearing members 20^f. In this form, the head 41 bears directly against the head of the thrust member. The rotation of the head 41 varies the distance between the crank arm 19^f and the head (not shown) of the thrust member.

Fig. 9 shows diagrammatically an arrangement of levers for operating the embodiments of the adjusting member shown in Figs. 7 and 8. A pair of levers 43 is pivoted to the heads 41 and 42 and pivotally connected at their inner ends to an arm of a crank 44, the other end of which is connected by a connecting member 45 to a control lever 46. The movement of the control lever 46 is transmitted through the linkage to the heads 41 and 42 which may be rotated thereby to the desired position.

There is illustrated in Fig. 10 a mechanism for lifting ties with respect to the cutters. A frame 47 disposed about the cutter is carried on swingable supporting members 48 which are pivotally connected to the frame 47 whereby the frame 47 may be raised or lowered by rotation of the supporting members 48 but will be maintained in horizontal position at all times. A crank 49 and link 50 are provided for moving the frame 47. The frame 47 is arranged to support the ties as they are carried past the cutter 3^j and may be raised or lowered to determine the depth of the cut.

This mechanism may be employed in place of the cradle mechanism where the ties to be gained are so uniform that no adjustment for irregularities needs to be made. The arrangement may also be employed in combination with the cradle mechanism to lift from the cradles ties in which only very shallow cuts need be made.

It should be obvious that the present invention is not limited to machines for gaining railroad ties but may be applied to any type of wood working machine wherein it is desirable that the position of the work piece be adjusted with respect to the cutting mechanism.

I claim:

1. In a tie adzing machine, cutting means, means for transporting ties successively past said cutting means, means for supporting a tie for a gaining cut by said cutting means, means for lifting said supporting means with respect to said cutter, means controlled by the shape of said tie for regulating the extent of movement of said supporting means, and means in addition to said regulating means for adjusting the extent of movement of said supporting means.

2. In a tie adzing machine, in combination, a cutter, a carrier for moving ties suc-

cessively past said cutter, a cradle tiltably mounted adjacent said cutter, means for lifting said cradle, means controlled by the tilting of said cradle for determining the extent of lift of the cradle, and additional means operable during the working of the machine for controlling the lifting of said cradle.

3. In a tie adzing machine, in combination, a cutter, a carrier for moving ties successively past said cutter, a cradle tiltably mounted adjacent said cutter, means for lifting said cradle, means controlled by the tilting of said cradle for determining the extent of lift of the cradle and manual means operable during the working of the machine for controlling the extent of lift of the cradle.

4. In an adzing machine, in combination, a cutter, means for transporting ties successively past said cutter, a cradle for supporting a tie in contact with said cutter for a gaining cut, means including a thrust member for lifting said cradle, a driving member normally spaced from said thrust member and having a fixed upward movement, and a member interposed between said last members for transmitting at least a portion of the upward movement of said driving member to said thrust member.

5. In an adzing machine, in combination, a cutter, means for transporting ties successively past said cutter, a cradle for supporting a tie in contact with said cutter for a gaining cut, means including a thrust member for lifting said cradle, a driving member normally spaced from said thrust member and having a fixed upward movement, a member interposed between said last members for transmitting at least a portion of the upward movement of said driving member to said thrust member, and means mounting said interposed member for movement to vary the extent of movement transmitted to said thrust member.

6. The invention as set forth in claim 5, wherein said interposed member has an inclined surface bearing against one of said other members.

7. The invention as set forth in claim 5, wherein said interposed member has a stepped surface bearing against one of said other members.

8. In a tie adzing machine of the type including a cutter, a cradle, and means supporting said cradle for upward movement in accordance with the extent of irregularity of a tie, a member for adjusting the extent of movement of said cradle, and means operable during the working of the machine for controlling the adjusting effect of said member.

9. In an adzing machine, in combination, a cutter, means for moving ties successively past said cutter, a cradle for supporting a tie for a gaining cut by said cutter, means for lifting said cradle in accordance with the amount of irregularity in the shape of said

tie, said lifting means including a thrust member, a lifting member having fixed upward movement and a member for transmitting to said thrust member at least a portion of the movement of said lifting member, and means including said last member operable independently of the shape of said tie for varying the extent of the movement of said lifting member that is transmitted to said thrust member.

10. In an adzing machine, in combination, a cutter, a cradle for supporting a tie for a gaining cut by said cutter, means for lifting said cradle in accordance with the shape of the tie, said means including a thrust member and a lifting member having a fixed lifting movement and a member for transmitting at least a portion of the movement of said lifting member to said thrust member, and means operable during the working of the machine for adjusting the initial position of said lifting member.

11. In an adzing machine, the combination with a cutter, a cradle for supporting a tie in position for a gaining cut by said cutter, means for lifting said cradle in accordance with the shape of the tie to thereby effect a gaining of the tie in accordance with the shape thereof, and means for vertically positioning said tie independently of said cradle.

In testimony whereof, I affix my signature.

JESSE C. COOK.
